(57) **CLAIM**

The ornamental design for a packaging cup, as shown and described.

DESCRIPTION

FIG. 1 is a top, side perspective view of a packaging cup showing our new design;

FIG. 2 is a front elevation view of the packaging cup of FIG. 1;

FIG. 3 is a top view of the packaging cup of FIG. 1;
FIG. 4 is a side elevation view of the packaging cup of FIG. 1;
FIG. 5 is a rear elevation view of the packaging cup of FIG. 1;
and,

FIG. 6 is a bottom view of the packaging cup of FIG. 1.

The broken line representations of items in FIGS. 1-6 are for purposes of illustration only, and form no part of the claimed design.

1 Claim, 3 Drawing Sheets

FIG. 1

FIG. 2

FIG. 3

FIG. 4

FIG. 5
